Dana Oster, LLC(57) **CLAIM**The ornamental design for a carrying case, as shown and
described.

DESCRIPTION

FIG. 1 is a perspective view of the carrying case of my new
design;

FIG. 2 is a front view thereof;

FIG. 3 is a rear view thereof;

FIG. 4 is a first side view thereof;

FIG. 5 is a second side view thereof;

FIG. 6 is top view thereof; and,

FIG. 7 is a bottom view thereof.

The straps of the carrying case are shown with a symbolic
break in length. The appearance of any portion of the article
between the break lines forms no part of the claimed design.**1 Claim, 7 Drawing Sheets**| (56)	References Cited
